UNITED STATES PATENT OFFICE.

HERBERT W. OWEN, OF MILLBURY, ASSIGNOR TO GEORGE DRAPER & SONS,
OF HOPEDALE, MASSACHUSETTS.

THREAD-TENSION DEVICE FOR LOOM-SHUTTLES.

SPECIFICATION forming part of Letters Patent No. 546,677, dated September 24, 1895.

Application filed February 23, 1895. Serial No. 539,323. (Model.)

To all whom it may concern:

Be it known that I, HERBERT W. OWEN, a citizen of the United States, residing at Millbury, in the county of Worcester and Commonwealth of Massachusetts, have invented certain new and useful Improvements in Thread-Tension Devices for Loom-Shuttles, of which the following is a specification.

5 My invention relates particularly to a thread-tension device for loom-shuttles.

10 My improvement consists in a piece of wire bent into the required shape and secured to the frame of the shuttle or suitably mounted in a plate adapted to be secured to the frame 15 of the shuttle, as will more clearly appear upon reference to the drawings, in which—

Figure 1 is a plan view of the shuttle and bobbin, showing my improved device attached thereto. Fig. 2 is a side view of the shuttle. 20 Fig. 3 is an end view of the tension device mounted in the plate by which it is secured in place. Fig. 4 is a plan view of the plate and a top view of a part of the tension device, illustrating the manner in which the latter is 25 attached to the plate. Fig. 5 is a bottom view of the plate and tension device seated therein. Fig. 6 is a longitudinal sectional view of the plate and tension device on the line 6 6, Fig. 4, looking in the direction of the arrow. Fig. 30 7 is a vertical sectional view of the plate and side view of the tension device on the line 7 7, Fig. 4, looking in the direction of the arrow. Fig. 8 is a perspective view of the tension device separated from the plate. Fig. 9 is a perspective view of the plate alone, showing particularly the means by which the tension device is secured in place. Fig. 10 is a view of the tension device made out of wire square in cross-section, also showing the adjustment of 35 the thread in the tension device when the same is in operation.

40 In Fig. 1, 1 is the shuttle-frame. 2 is the bobbin. 3 is the plate in which the tension device is mounted and may be secured to the shuttle-frame in any desired manner. It may conveniently be done by means of the screw 45 4. 5 is the tension device, which consists of a piece of wire bent into substantially a U shape somewhere near its middle portion, with

each end bent at right angles to the middle portion and wound into a coil, the two coils being wound away from a common center, but in the same direction.

50 It is obvious that the members of the coils may be multiplied at pleasure and the tension upon the thread increased or diminished by increasing or diminishing the distance between the members. The members of the coils may be brought sufficiently near together to exercise a direct pressure upon the thread, 55 which may be found desirable.

In the drawings I have shown two members 6 and 7 at one extremity and two members 8 and 9 at the other extremity, the former coil terminating at 10 and the latter terminating at 11.

60 It will be noted, upon referring to Figs. 8 and 10, that the outer coil terminating at 11 is raised at its lowest point somewhat above the immediately adjoining coil, for a purpose 70 hereinafter to be explained.

The tension device may be mounted in the supporting-plate in any suitable manner. The method which I prefer is illustrated in the drawings, in which the plate is shown provided with a saddle-piece 12, upon which the U-shaped part of the tension device is supported. The coils are sprung over the projections 13 and 14 into the hollow seat 15, which 75 may conform in shape to the coils. The upward projection 16 prevents the tension device from slipping off the saddle, and it is thus held securely in place. The end 17 of the supporting-plate is bent downwardly in order that the thread may not work out, and the 80 angle 18 on the underside of the supporting-plate is rounded in order that the thread may be readily guided into the tension device 85 without catching.

The modification in Fig. 10 shows the tension device made of wire square in cross-section, and is designed to catch any bunch which may be in the thread, thus breaking the latter and preventing any imperfect work in weaving.

90 The outer side of the supporting-plate may be rounded, so as to avoid any possibility of catching in the warp.

Having described the construction of my improved tension device, I will now indicate its mode of operation.

The thread from the bobbin is passed under 5 the end 17 of the supporting-plate and is guided over the projecting ends 10 11 of the tension device until the thread occupies substantially the position shown by the horizontal line in Fig. 10.

10 c Reference has been made to the fact that the outer coil terminating at 11 is somewhat higher than the lowest point of the next adjoining coil. This is to prevent the thread from working out of the tension device.

15 15 This device is also self-threading, the thread being drawn off the bobbin when the shuttle leaves the box, and when the shuttle returns the thread is drawn under the end 17 of the supporting-plate and delivered to the tension 20 device by passing over the upwardly-turned ends 10 and 11.

I do not confine myself to any special form 25 of shuttle or bobbin, or to any particular means for securing the tension device to the shuttle-frame, or to any form of supporting-plate, or to any particular size of wire for the tension device, or to any particular number of coils therein, or to any particular relative arrangement of the parts.

30 30 Having described my invention, what I claim as new, and desire to secure by Letters Patent, is—

1. In combination with a shuttle-frame, a supporting plate and a tension-device of wire, 35 consisting of two coils of a plurality of members each, said coils being formed in the same direction away from a common center, and having an intermediate portion adapted to be secured to the supporting-plate, the ends of 40 said coils being free and adapted to receive a thread, substantially as shown and described.

2. In combination with a shuttle-frame, a supporting plate and a tension-device of wire, 45 consisting of two coils of a plurality of members each, said coils being formed in the same direction away from a common center, and having an intermediate portion adapted to be secured to the supporting-plate, the ends of 50 said coils being free and adapted to receive a thread, the outer member of the outer of said coils being higher at its lowest point than the next adjoining member, whereby the 55 thread may be prevented from working out of the tension device, substantially as shown and described.

3. In combination with a shuttle-frame, a supporting plate and a tension-device of wire, 60 consisting of a middle portion, bent substantially into a U-shape adapted to be secured to the supporting-plate, and terminating in two coils, of a plurality of members each, substantially at right angles with said middle portion, said coils being formed in the same direction away from a common center, the 65 ends of said coils being free and adapted to

receive a thread, substantially as shown and described.

4. In combination with a shuttle-frame, a supporting plate adapted to receive a tension-device and a tension-device of wire, consisting of a middle portion, bent substantially into a U-shape, and terminating in two coils of a plurality of members each, substantially at right angles with said middle portion, said coils being formed in the same direction, away 70 from a common center, said supporting plate having a saddle piece and upward projection therefrom, and a hollow seat, whereby said tension device may be securely held in place, substantially as shown and described. 75

5. In combination with a shuttle-frame, a supporting-plate adapted to receive a tension-device and hold it in position, and a tension-device of wire, consisting of a middle portion, bent substantially into a U-shape, and terminating in two coils of a plurality of members each, substantially at right angles with said middle portion, said coils being formed in the same direction, away from a common center, the upper face of said supporting plate terminating in a downwardly-turned end, and having its lower surface curved, whereby the thread may be prevented from working out, and may be delivered to the tension-device, substantially as shown and described. 80

6. In combination with a shuttle-frame, a supporting plate and a tension-device of wire, consisting of a middle portion bent substantially into a U-shape, adapted to be secured to the supporting-plate, and terminating in two coils of a plurality of members each, substantially at right angles with said middle portion, said coils being formed in the same direction away from a common center, the ends of said coils being free, and adapted to 90 receive a thread, and the outer member of the outer of said coils being higher at its lowest point than the next adjoining member, whereby the thread may be prevented from working out of the tension device, substantially as shown and described. 95

7. In combination with a shuttle-frame, a supporting plate and a tension-device of wire, substantially square in cross-section, consisting of a middle portion bent into a U-shape, 100 adapted to be secured to the supporting-plate, and terminating in two coils of a plurality of members each, substantially at right angles with said middle portion, said coils being formed in the same direction away from a common center, the ends of said coils being free and adapted to 105 receive a thread, whereby any enlargement in the thread will cause it to break, substantially as shown and described. 110
